UNITED STATES PATENT OFFICE.

JOHN E. ROWAN AND LOUIS F. BAUMAN, OF VIRGINIA, MINNESOTA.

WASHING-BOILER.

1,074,528.

Specification of Letters Patent. Patented Sept. 30, 1913.

Application filed September 11, 1912. Serial No. 719,802.

To all whom it may concern:

Be it known that we, JOHN E. ROWAN and LOUIS F. BAUMAN, citizens of the United States, residing at Virginia, in the county of St. Louis and State of Minnesota, have invented new and useful Improvements in Washing-Boilers, of which the following is a specification.

The general object of this invention is the provision of a washing boiler adapted to receive articles of clothing therein, whereby the latter may be cleansed by injecting steam into said boiler, novel means being provided for the escape of the steam after the same has circulated through the clothes.

In carrying out the object of the invention generally stated above, it will be understood, of course, that the essential features thereof are susceptible to changes in details and structural arrangements, one preferred and practical embodiment being shown in the accompanying drawing, wherein—

Figure 1 is a side elevation of the boiler constructed in accordance with the invention. Fig. 2 is a vertical longitudinal sectional view thereof. Fig. 3 is a top plan view. Fig. 4 is a detail perspective of the means for permitting the escape of steam from the boiler.

Referring more particularly to the accompanying drawing, in which like reference characters designate similar parts, it will be seen that the invention comprises a reservoir 5 which is tapered throughout its entire length, said reservoir being provided with a substantially cylindrical portion 6 and a reduced offset portion 7 communicating with said cylindrical portion. The cylindrical portion 6 is provided in the top thereof with a rectangular opening 8 which is adapted to be closed by means of a door 9, said door, when closed, being adapted to render the reservoir 5 air tight. The outer end of the offset portion 7 has mounted therein adjacent the bottom thereof a steam inlet pipe 10 which is adapted to be connected to a suitable source of steam supply (not shown). After a number of articles of clothing have been placed in the reservoir 5 through the opening 8 therein and the door 9 placed in position, steam is injected into the reservoir through the medium of the pipe 10 and said steam is under sufficient pressure for the same to thoroughly circulate through the said articles

of clothing and any condensed steam may pass off through the drain pipe 11 which is mounted in the bottom of the cylindrical portion 6 of the said reservoir. Adjacent 60 the top of the cylindrical portion 7 and on each side thereof, the same is provided with a plurality of transverse openings 12. Each of the openings 12 is adapted to receive one of the angular extensions 13 of the steam exhaust pipes 14 which extend vertically on each side of the cylindrical portion 6 and which communicate at their lower ends with the pipes 15, said latter pipes extending at right angles to the pipes 14 and longitudinally of the reservoir 5 to a point at the rear thereof. Here the pipes are bent to extend transversely of the rear of the reservoir and are adapted to communicate with an outlet pipe 16. It will thus be seen that 75 after the steam has circulated through the clothing in the reservoir the same will rise therein and pass out through the openings 12 into the pipes 14, thence to the pipes 15 and 16 and thence to the atmosphere. 80

The shape of the boiler lends importance to the structure in that by reason of the reduced space immediately adjacent the inlet as compared with the enlarged circular space beyond the same we provide for the 85 reception of the clothes in said circular space and prevent their entrance into the reduced space. By this means steam entering the boiler through the inlet pipe is permitted to expand and thereby reach all of 90 the clothes in the boiler and avoid the disadvantages which would be present in this stationary type of boiler were steam directed in a single jet against one portion of the clothes only. By this construction we gain 95 advantages of a rotary boiler without necessitating the movement of any part thereof.

From the foregoing description taken in connection with the accompanying drawing, 100 it will be seen that the invention contemplates providing a washing boiler which is simple in construction thus reducing the cost of manufacture of the same to a minimum, and which is durable and effective in carrying out the purpose for which it is designed. 105

What is claimed is:—

A wash boiler comprising a receptacle tapered throughout its length and formed to provide a substantially cylindrical portion 110 and a longitudinally aligned offset portion in communication with the cylindrical por-

tion, a steam inlet pipe opening into the offset portion remote from the cylindrical portion and adjacent the bottom of the receptacle and steam exhaust means including 5 a pipe communicating with the interior of the cylindrical portion adjacent the top of the receptacle.

In testimony whereof we affix our signatures in presence of two witnesses.

JOHN E. ROWAN.
LOUIS F. BAUMAN.
